UNITED STATES PATENT OFFICE.

JAMES CORYDON DE LANEY AND FRANK L. DE LANEY, OF PORTERSVILLE,
CALIFORNIA.

AUTOMATIC CONTROLLER FOR MOTORS.

Application filed March 14, 1921. Serial No. 452,112.

To all whom it may concern:

Be it known that we, JAMES C. DE LANEY and FRANK L. DE LANEY, citizens of the United States, residing at Portersville, in the county of Tulare and State of California, have invented certain new and useful Improvements in Automatic Controllers for Motors, of which the following is a specification.

10 Our invention relates to a controller designed particularly for use in connection with motor vehicles, and more particularly with the internal combustion motor used in connection therewith, its principal object 15 being to automatically prevent the operation of the motor under certain conditions.

The invention consists first in the means for controlling the operation of the motor by the short circuiting of the ignition circuit, second in the means for operating the controller by the variation in pressure in the lubricating system, and further in various features of construction and operation as hereinafter set forth.

25 With the above mentioned and other objects in view, the invention consists in the novel construction and combination of parts hereinafter described, illustrated in the accompanying drawings, and set forth in the 30 claim hereto appended, it being understood that various changes in the form, proportion, size and minor details of construction within the scope of the claim may be resorted to without departing from the spirit 35 or sacrificing any of the advantages of the invention.

To more fully comprehend the invention, reference is directed to the accompanying drawings, wherein—

40 Figure 1 is a view in vertical section of the preferred embodiment of our invention taken on line 1—1 of Figure 3, and viewed in the direction of the arrows.

45 Figure 2 is a view similar to Figure 1, but taken on line 2—2 of Figure 3 at right angles to line 1—1, and viewed in the direction of the arrows.

Figure 3 is a view in top plan of our invention.

50 Figure 4 is a horizontal sectional view taken on line 4—4 of Figure 1, and

Figure 5 is a diagrammatic view of the controller associated with an internal combustion motor and its associated mechanism.

55 Referring more particularly to the several

views of the drawings wherein like characters of reference designate corresponding parts, 1 indicates a cylinder of an internal combustion motor. The crank shaft and other parts thereof which require lubrication are supplied with a lubricating medium through the pump 2 which withdraws the same from a supply or sump 3 preferably the lower part of the motor crank casing, the pump forcing the lubricant through the pipe 4 to the desired points to be lubricated. Co-operating with the cylinder 1 is an igniting device or spark plug 6 supplied with electric energy through the circuit 7 in which is mounted a battery or any form of dynamo electric machine 8 for supplying a spark for the plug 6. The controller for controlling the ignition circuit in accordance with the variation of pressure within the lubricating feed pipe 4 is constructed as follows:

Within the line 4 is a T-coupling 9 into which threads a nipple 10 extending from the lower end of a cup casing 11, which casing is formed on its interior with a chamber 12. The inner wall surface of the casing 11 is formed with an annular seat 13 and normally closing said casing is a cover or closing member 14, formed adjacent its peripheral edge with an annular skirt 15 for reception within the chamber in the casing 11, and the lower edge of the skirt is adapted to lie in slight spaced relation to the seat 13 when the cover is in position. A threaded connection 16 between the inner wall surface of the casing 11 and the upper exterior surface of the skirt 15 provides a means for detachably securing the cover in position.

A flexible diaphragm 17 retained between gaskets 18 between the seat 13 and the lower edge of the skirt 15 divides the chamber 12 into upper and lower compartments 19 and 20, the compartment 20 being open to the fluid pressure in the pipe 4, as illustrated in Figures 2 and 5 of the drawings, and the upper chamber 19 being separated and maintained apart from contact with the circulating lubricating medium. Extending upwardly centrally of the diaphragm 17 is a supporting and guide post 21, the upper end of which is adapted for reception within the guide opening 22 in the under face of the closure member 14, and said post carries a suitable mounting 23 of insulation.

material, which mounting on its upper surface is provided with an annular contact ring 24. The ignition circuit 7 is interrupted adjacent the controller and portions of 5 the line forming the same connect with the respective binding posts 25 passing through the closure member 14 and held therein within the insulating sleeves 26 by terminal and clamp nuts 27. The lower end of each binding post is provided with a tubular bore 10 within which is mounted for longitudinal reciprocation, a contact point 28 normally forced downwardly by the spring 29 and limited in its movement by a pin 30 preferably carried by the post. The closure member 14 is provided with a normally closed filling opening 30', through which is adapted to be deposited within the upper chamber 19, a suitable fluid such as oil for extinguishing or quenching the spark which may be caused by the making or breaking of the connection between the members 28 and the ring 24, and thus preventing corrosion of these contact points. The provision of the 20 spring held members 28 ensures a uniform contact between both members and the ring 24, and also permits of the ready movement of the diaphragm 17 by the lubricating fluid pressure.

25 An auxiliary circuit 31 mounting a switch 32 connects with ignition circuit 7 at opposite sides of the binding posts 27, and the manual closing of the switch 32 eliminates the controlling of the motor ignition circuit by the oil pressure, and this auxiliary circuit is provided in cases where the motor oil is renewed and consequently the pressure within the line is lowered until such time as the motor has been operated for a short 30 period and the pressure has been permitted to build up.

35 It will be observed that when the switch 32 is in open position, and the motor is operating, the pressure in the oil line 4 will 40 act against the diaphragm 17 and raise the same to complete the ignition circuit

through the posts 27 and ring 24, and should for any reason the oil pressure in the line 4 fail either through the failure of the pump 2 or the failure to maintain a sufficient 50 volume of oil to be acted on by the pump 2, the release of pressure on the under side of the diaphragm 17 will permit the same to drop and assume its normal position, indicated in Figure 1, at which time the motor 55 will automatically stop due to the breaking of the ignition circuit. To again start the motor, it will be necessary to close the switch 32 until such time as the pressure within the line 4 builds up sufficiently to 60 close the ignition circuit 7.

Having thus described our invention what we claim as new and desire to secure by Letters Patent of the United States is as follows:—

A circuit controlling device comprising a casing formed with a hollow body provided with an annular flange near the base of its inner wall, a flanged cover provided with a skirt for threaded reception within the body 70 and for co-operation at its lower end with said annular flange, a flexible diaphragm disposed transversely of the body and supported by said flange for dividing the body into two chambers, a pair of inwardly 75 pressed spring held contact points carried by said cover above said diaphragm, a post extended upwardly from the center of said diaphragm, said cover provided with a guide opening within which the end of said 80 post reciprocates, a support extended laterally on each side of said post, a contact ring carried by said support, a connection between the lower chamber and a source of fluid supply under pressure, and a packing ring in contact with opposing faces of the disk at its periphery to afford the maximum flexibility thereto for its operation.

In testimony whereof we have signed our names to this specification.

JAMES CORYDON DE LANEY.

FRANK L. DE LANEY.
